UNITED STATES PATENT OFFICE.

GEORGE C. SAWYER, OF CANTON, NEW YORK.

DESIGN FOR A JAR.

SPECIFICATION forming part of Design No. 19,516, dated December 17, 1889.

Application filed August 9, 1889. Serial No. 320,307. Term of patent 7 years.

To all whom it may concern:

Be it known that I, GEORGE C. SAWYER, a citizen of the United States, residing at Canton, in the county of St. Lawrence and State of New York, have invented and produced a new and original Design for Jars, of which the following is a specification, reference being had to the accompanying drawings, forming a part thereof.

10. Figure 1 is a sectional perspective view of a jar showing my design. Fig. 2 is a top edge view, these views being deemed necessary and sufficient to illustrate my design.

15. The leading or characteristic feature of my design consists in a cylindric jar having an enlarged open mouth, the exterior contour whereof passes from the cylindric form into an abrupt cyma recta, as shown, the interior contour whereof, on the contrary, passes from 20. the cylindric form into an abrupt outwardly-directed beveled field or surface connecting the said shoulder with a still further outwardly-placed final upper cylindric section, which latter section is provided upon two opposite

quadrants of its circular contour with an inwardly-directed lip or projection, as shown.

In more particular detail, my design shows in B the cylindric jar having the enlarged open mouth H, the exterior of which is a cyma recta. The right-angular shoulder E bounds the inner cylinder at the top, which shoulder is surrounded by the beveled field or surface C, which in turn passes into the final cylindric section F.

25. A A represent each an inwardly-directed lip or projection upon opposite quadrants of the circular contour of the mouth, the surface and shape of the jar being clearly shown in the drawings.

30. What I claim as of my invention, and desire to secure by Letters Patent of the United States, is—

35. The new and original design for a jar, as herein shown and described.

GEORGE C. SAWYER.
